CIRCUIT BREAKER

Winthrop M. Leeds, Wilkinsburg, Pa., and Ennio Ortensi, Bergamo, Italy, assignors to Westinghouse Electric & Manufacturing Company, East Pittsburgh, Pa., a corporation of Pennsylvania

Application May 28, 1937, Serial No. 145,273

23 Claims. (Cl. 200—150)

This invention relates to high-power circuit interrupters of the liquid-immersed type, and more particularly, to circuit interrupters that utilize an arc restraining channel or slot in which the arc is subjected to strong deionizing action by turbulently intermixing un-ionized gas and liquid particles with the arc stream. The instant invention is also, in certain aspects, an improvement of the inventions set forth and broadly claimed in the applications of B. P. Baker, Serial No. 230,946, filed September 21, 1938, and W. M. Leeds et al., Serial No. 144,626, filed May 25, 1937, both of which are assigned to the assignee of this application.

Heretofore attempts have been made to hasten the deionization of the arc by driving it into a restricted passage and subjecting it to strong cross blasts of oil and gas immediately following the establishment of the arc, irrespective of the instantaneous current conditions. We have discovered that forcing an arc into a very narrow slot and subjecting it to strong cross blasts during the major portion of the alternating-current cycle, particularly when instantaneous values of current are relatively large, produces a harmful effect on the interrupting ability of the arc rupturing device. Poor performance under these conditions is attributed to the resultant high arc voltage and high internal pressure developed within the interrupting structure. Our study of arc-interrupting phenomena reveals that circuit interrupter performance may be improved by adhering to the following steps in the method of treating the arc during the circuit-interrupting operation.

First, during the greater portion of time arc current is flowing, particularly in the region of the peak of the current wave, the arc should be disturbed as little as possible by cross blasts, restricting walls, or strong magnetic action, so as to keep the arc voltage and the consequent gas generation as low as possible; second, vents, passages and liquid flow should be arranged to drive the products of decomposition of the arc out of the arc chamber as fast as they are formed so as to maintain high dielectric in the arc chamber and keep the internal pressure reasonably low; and third, just prior to current zero when the arc current is relatively low, strong deionizing action should be brought into play, as for instance, subjecting the arc to turbulent cross blasts of liquid and gas, confining the arc within a restricted passage or rapidly moving or lengthening the arc. These methods of treatment to produce rapid deionization either singly or in

combination, though preferably the latter, insure complete interruption of the circuit at current zero.

The main object, therefore, of our invention is to provide means for improving the arc-rupturing ability of a circuit interrupter of the liquid-immersed type. 5

A further object of our invention is to provide a circuit interrupter in which arc extinction is accomplished by sequentially subjecting the arc to a longitudinal flow and cross blast of arc-extinguishing liquid and the products of decomposition of the arc. 10

A more specific object of our invention is to provide a circuit interrupter in which improved 15 performance is attained by effecting arc extinction in accordance with the steps enumerated above.

Other objects and advantages relate to details 20 of the interrupter structure whereby the aforementioned objects are obtained and will appear more fully in the following description taken in connection with the accompanying drawings, in which:

Figure 1 is a side elevation view partially in 25 section showing an embodiment of our invention;

Fig. 2 is a fragmentary view of the arc-extinguishing units of our circuit interrupter showing one of the arc-extinguishing units in vertical section;

Fig. 25 is a plan view of the arc-extinguishing unit shown in Fig. 24 as viewed along the line 45 XXV—XXV of Fig. 24;

Fig. 26 is a cross-sectional view taken along the line XXVI—XXVI of Fig. 24 and,

Fig. 27 is a fragmentary view partially in section showing the interrupter of Fig. 1 in the open 50 circuit position.

With particular reference to Fig. 1, the reference numeral 1 designates a cylindrical casing preferably of metal, which forms part of the housing of the circuit interrupter. The casing 1 is 55

provided with an annular top plate 3, which is adapted to support a cylindrical strain cylinder 5, preferably of insulating material, such as fibre or a material known to the trade as "Micarta." The lower portion of the strain member 5 is provided with a metallic flange member 7 which, in turn, may be bolted to the annular plate 3, thereby securing it against lateral and longitudinal movement. The upper end of the strain member 5 is also provided with a flanged metallic member designated at 9. To the flange 9 may be bolted a top plate 11. Surrounding the strain member 5 is a weather-proof casing 13 preferably of porcelain or some other suitable material having weather-resisting properties.

The weather-proof casing 13 in this instance, is adapted to rest at its lower end upon a metallic sub-casing 15. A metallic flange 17 secured to the lower edge of the weather-proof casing 13 permits bolting the latter casing to the sub-casing 15, as shown. A cork gasket 19 interposed between the casing 13 and the casing 15 provides a seal between these two casings so as to permit the annular space between the strain member 5 and the casing 13 to be filled with insulating liquid.

A resilient annular metal expansion member 21 having a C-shaped cross-section, is interposed between the upper end of the casing 15 and the top plate 11. A gasket 23 interposed between the resilient member 21 and the casing 13 provides the necessary seal for retaining the insulating liquid heretofore mentioned. A gasket may also be placed between the resilient member 21 and the top plate 11, as shown. The relative longitudinal dimensions of the strain member 5 and the weather-proof casing 13 are such that when they are in the assembled position, as shown, the resilient member 21 exerts a compressive force upon the casing 13. Thus the seal between the resilient member 21 and the weather-proof casing 13 is always maintained regardless of the difference in expansion of the inner strain member 5 and the outer weather-proof casing 13.

The top plate 11 is provided with a hanger plate 25 to which is secured an arc interrupting assemblage generally indicated at 27. The arc interrupting assemblage 27 may comprise a plurality of arc-extinguishing units 29, two of which are shown. Each arc-extinguishing unit 29 comprises a stack of plates, more specifically illustrated in Figs. 5 to 23 inclusive. These plates are assembled upon insulating tie rods 31, the ends of which are provided with metallic portions 33 which are threaded for the reception of clamping nuts 35. The two units 29 in this instance are supported in spaced relation with respect to each other by means of four spacing sleeves 37 assembled on the rods 31.

The uppermost arc-extinguishing unit 29 is suspended from the hanger plate 25 by four hanger rods 39, the lower portions of which are screw-threaded onto the respective metallic portions 33 of the tie rods 31 and the upper portions of which are screw-threaded and extend through the hanger plate 25 and are provided with nuts 41. A spacing sleeve 43 surrounds each of the hanger rods 39 and is disposed between the hanger plate 25 and the upper arc-extinguishing unit 29.

Each of the arc-extinguishing units 29 has an upper plate 45 preferably of metallic material, and as shown particularly in Figs. 5 and 6, is provided with a circular aperture 47 for the reception of a piston member to be described hereinafter, a rectangular aperture 49 for the reception of a

stationary contact member, two rectangular apertures 51, which serve as vent openings and a single circular aperture 53 which also serves as a vent opening. The following plate 55, as shown in Figs. 7, 8 and 9, as well as the remaining plates, 5 have a circular aperture 47. Plate 55, which is preferably of insulating material, such as fibre, also has a circular vent aperture 53. The aperture 47 in plate 55 communicates with a slot 57 of irregular outline. The lower end of slot 57 is provided with beveled surfaces 59 on either side thereof, as shown more clearly in Figs. 8 and 9, the purpose of which will appear hereinafter.

Plate 61 of fibre or other suitable insulating material, is disposed adjacent the plates 55. The 15 plate 61 as more clearly shown in Figs. 10 and 11, has a relatively wide slot 63 therein which slot joins the circular aperture 47. The sides of the slot 63 are provided with a plurality of, in this instance 3, notches or indentations 65, the central 20 one of which is considerably deeper than those on either side thereof.

The plate 61 also has an aperture 67 in alignment with the lower end of slot 63. The next plate in the stack is designated at 69 and is more 25 clearly shown in Figs. 12 and 13. This plate has circular apertures 47 and 53 positioned so as to axially align with the apertures 47 and 53 of plate 45. These apertures are joined by a slot-like passage 71 having a narrow restricted portion 73 30 adjacent the aperture 53 and a wider portion 75 adjacent the aperture 47.

Immediately following the plate 69 is a plate 77, which in the main is composed of insulating material such as fibre, and has a U-shaped insert 35 79 of magnetic material. The plate 77 in all other respects is similar in construction to plate 69. The insert of magnetic material 79, as shown, is disposed about the slot-like passage 71, and the purpose of which will appear more fully herein- 40 after.

The plate 77 is followed by a second plate 69. Adjacent plate 69 is a plate of greater thickness designated at 81 and shown in Figs. 16 and 17. The plate 81 has a configuration similar to that 45 of plate 61, except that the slot 83 is somewhat narrower than the slot 63 and also tapers in the direction towards the lower end thereof. The aperture designated at 85 is also somewhat wider than the aperture 67 in plate 61, thereby providing 50 for a narrower strip of material between the aperture and slot than in the plate 61. The intervening portions 87 and 68 of plates 81 and 61, respectively, serve as barriers, the purpose of which will be fully explained hereinafter. 55

The remaining plates of the stack, with the exception of several adjacent the lower end of the stack, which will be hereinafter described, comprise successive groups of plates 69, 77, 69 and 81 in the order named. Towards the lower 60 end of the stack is provided a plate designated at 89 which is similar to plate 77 with the exception that the vent aperture 53 has been omitted. Plate 89, however, is disposed between plates 69 in a manner similar to the arrangement of the 65 plates above. The second to the last plate in the stack is designated at 91 and is similar to plates 61 and 81 with the exception that the slot 93 has a width intermediate that of the aforementioned plates. The plate 91 also distinguishes from 70 plates 61 and 81 in that the slot 93 is extended so as to eliminate the barrier such as barriers 68 and 87 found in plates 61 and 81, respectively.

The lowermost plate of the stack, which is designated at 95 has considerably more thickness 75

than any of the previously described plates, is preferably composed of insulating material, as fibre or the like, and differs substantially from the construction of the foregoing plates. The aperture 47 in this instance, is threaded for the purpose of receiving a bushing to be hereinafter described. Adjacent the aperture 47 is a short slot 97 having a depth substantially equal to one-half the thickness of the plate.

From the foregoing specific description of the individual plates comprising the stack of each unit 29, it will be apparent that when the various plates are assembled upon the tie rods 31, the apertures 47 will be in alignment and form a cylindrical passage 101. The slots 71 in plates 69, 77 and 89 generally define the outlines of an arc passage 103. The passage 103 has a narrow slot-like restricting portion 105 defined by the slot portion 73. The enlarged portion 75 of the respective slots 71 defines the walls of an enlarged portion 107 of the passage 103, which enlarged portion communicates with the cylindrical passage 101. The arrangement of this passage is more clearly shown in Fig. 4.

As indicated in Figs. 2 and 3, the upper plate 45 of each unit 29 is provided with a contact-carrying member 109, which is mounted transversely across the aperture 49 and is retained in position by two spaced bolts 111, the lower ends of which are secured to the plate 45. The contact-carrying member 109 has a limited amount of movement in the vertical direction, determined by a coil spring 113 interposed between the head of each bolt 111 and the contact-carrying member. The springs 113 thus bias the contact-carrying member 109 toward the plate 45.

The contact-carrying member 109 is provided with a contact 115 secured to the lower side thereof and adapted to extend through the aperture 49 and into the slot 57 of plate 55. The plate 45 also carries an upper arcing horn 117 secured thereto by screws 119 and disposed so as to extend into the slot 57 of plate 55 immediately adjacent the stationary contact 115.

The aperture 47 in plate 45 is provided with a guide bushing 121 for the reception of a piston 123 movable in the cylindrical passage 101. Though the piston 123 may have a smooth outer surface it is preferably of tubular form having circumferential grooves formed therein and is also preferably of insulating material such as fibre or the like. The circumferential grooves increase the break-down voltage longitudinally of the piston and permit a flow of liquid from the remote side of the passage 101 towards the arc passage 103. The piston 123 also forms a part of the movable contact assemblage including a movable contact 125 of rectangular cross-section integrally secured to a cylindrical portion 127, which in turn is mounted upon a tubular metallic coupling 129.

The metallic coupling 129 is adapted to receive a tie rod 131 preferably of insulating material, which is adapted to extend through the bore of the piston 123 and is provided at its upper end with a metallic coupling member 133. The metallic coupling member 133 has a threaded portion shown at 135 for the purpose of receiving a spanner nut 137, whereby the piston 123 and the movable contact 125 with its carrier 127 are accordingly maintained in the assembled position. The upper metallic coupling member 133 is joined to an operating rod 139, which as more clearly shown in Fig. 1, extends upwardly through hanging plate 25 and is provided at its upper end with

a guide plate 141. Guide plate 141 is adapted to slide within a cylindrical housing 143 secured by bolts 145 to the top plate 11. The housing 143 is closed at its upper end so as to provide a bearing surface for an accelerating spring 147 interposed between the closed end of the casing and the guide plate 141. The accelerating spring 147 urges the operating rod 139 downwardly and consequently, carries the piston 123 and the movable contact 125 to the open circuit position as indicated in Fig. 2.

In the particular arrangement shown in Figs. 1 and 2, employing two arc-extinguishing units 29, the lower metallic coupling element 129 is coupled to the upper magnetic coupling element 133 of the lowermost unit 29. Thus, the two pistons 123 in each unit 29 are coupled axially for simultaneous actuation. The metallic coupling member 129 of the lowermost unit has provided thereon a pair of laterally yielding contact fingers 151 which are adapted to engage a contact actuating member 153, in this instance having a lower reduced section 155 of circular cross-section adapted for sliding movement in a tubular guide member 157 mounted through the base of casing 1. Contact actuating member 153 is disposed in axial alignment with operating rod 139 and the tie rods 131, so that if a reciprocating motion is imparted to the actuating member 153, a corresponding reciprocating motion will be imparted to the two pistons 123 and their associated contacts 125. In this manner, the movable contacts 125 are operated into and out of engagement with their respective stationary contacts 115.

The contact actuating member 153 is adapted to be operated by a suitable straight-line motion mechanism generally indicated at 159, which in turn, is provided with a crank arm 161, adapted to be actuated by a rod 163 by any suitable operating mechanism, not shown.

When the interrupter is in the closed circuit position, as shown in Fig. 1, the electrical circuit therethrough comprises the line terminal 165 forming part of the top plate 11, a flexible conductor 167 connecting the top plate 11 with the contact-carrying member 109 of the upper arc-extinguishing unit 29, as shown at 169. The circuit proceeds from the contact-carrying member 109 to the contact 115, which is in engagement with the movable contact 125. The movable contact 125 in turn is secured to the contact-carrying member 127 which has a fixed engagement with the metallic coupling member 129. The metallic coupling member 129 is, in turn, secured to metallic coupling member 137 of the next adjacent unit 29.

In the lower unit 29, a flexible shunt 171 is interposed between the nut 137 and the piston 123. The flexible shunt 171 is preferably divided as shown in Fig. 3, and has the free ends secured to the respective ends of the contact-carrying member 109 by bolts 173 as shown. Thus the circuit continues from contact-carrying member 109 of the lowermost unit through its respective fixed contact 115, to its movable contact 125, and to the lower metallic coupling member 129. From the metallic coupling member 129 the circuit proceeds to the contact fingers 151 and hence to the contact actuating member 153. The latter member is provided with a flexible shunt connection 175, which connects to a terminal 177, which terminal is connected by a conductor 179 to the base of casing 1. The base of casing 1 may preferably be provided with a

terminal 181 which serves as the other line terminal of the interrupter.

Each of the arc-extinguishing units 29 is also provided with a lower arcing horn 183, in this instance, secured as by screws or bolts 185 to the lower plate 95. The arc horn 183 is disposed within the slot 93 of the plate 91 and has one end adjacent the movable contact 125 when the latter is moved to the full open position, as shown in Fig. 2. A flexible connection 187 secured to the bolt 185 joins the arc horn 183 of the upper unit 29 with the contact-carrying member 109 of the lower unit 29, as shown in Fig. 2. A similar connection 189 is made to the resilient contacts 151 for the lowermost unit 29.

The operation of the interrupter during circuit interruption is as follows. Upon the occurrence of an overload in the connected circuit or upon the tripping of the operating mechanism (not shown), the rod 163 is actuated upwardly, which in turn, actuates the mechanism 159 so as to move the contact actuating member 153 to its lowermost position. The movement of the actuating member 153 downwardly is accelerated by the action of spring 147, thereby greatly increasing the speed of separation of the contacts 115 and 125 in each unit. Upon the separation of the contacts 115 and 125, an arc is established within the enlarged portion 107 of the arc passage 103. During the establishment of the arc the piston 123 has been moved into the cylindrical chamber 101, thereby forcing arc-extinguishing liquid, in which the units 29 are submerged, upwardly past the moving contact 125 and longitudinally of the arc. This rapidly moving stream of liquid carries off the gases produced by the action of the arc on the arc-extinguishing liquid, forcing them upwardly away from the arc stream adjacent either side of the upper arcing horn 117 through the slot 57 of plate 55, past the bevelled surfaces 59 of the plate 55 and finally to the two rectangular vent openings 51. The disposition of the vent openings 51 with respect to the slot 57 of plate 55 and the upper arc horn 117 is more clearly shown in Fig. 4a. If the arc has been established at a time in the current cycle corresponding to relatively high instantaneous current, the arc will have a relatively large cross-sectional area, but due to the relatively wide portion 107 of the arc passage 103, it will not be materially restricted.

On account of the magnetic reaction of the U-shaped plates 79 inserted in the plates 77 and 89, the arc will be biased towards the entrance of the restricted portion 105 of the passage 103. However, due to the large arc section and the relatively weak pull of the magnetized plates 79, the arc will not be moved into the restricted portion, but will be permitted to play in the enlarged portion 107 of the arc passage 103. However, as the instantaneous value of the current decreases, the cross-sectional area of the arc also decreases and at a point just prior to current zero when the arc section has decreased sufficiently, the arc will be moved laterally by the magnetic reaction of the U-shaped plates 79 into the restricted portion 105 of the arc passage 103. As soon as the arc is transferred to the restricted portion 105, the electrical circuit through each interrupting unit 29 proceeds from the contact-carrying member 109, the top plate 45, the upper arc horn 117, through the arc stream to the lower arc horn 183, the bolt 185, flexible connector 187 to the contact-carrying member 109 of the lower unit 29. The circuit

through the lower unit 29 is similar to that of the upper unit with the exception that the lower arc horn 183 of the lower unit is connected by flexible conductor 189 to the contacts 151.

Movement of the arc into the restricted portion 105 of the arc passage 103 is also assisted by the pressure within the enlarged portion 107 of the arc passage created by the piston 123. As soon as the arc enters the restricted portion 105, it is subjected to a strong cross blast of oil and gas as a result of the intimate engagement of the arc with the liquid entrapped by the notches 65 forming pockets along the walls of the passage 103. The gas thus produced must escape through the arc towards the rearward side of the restricted portion 105 of the passage and rises through the vent openings 53 which are in alignment so as to form a vent shaft for the entire stack of plates. This vent shaft communicates with the restricted portion 105 of the arc passage by way of the restricted slot portion 73 in the plates 69, 77 and 89. The portions 68 and 87 of plates 61 and 81 serve as barriers to prevent the arc from moving entirely into the vent shaft 53.

Inasmuch as the restricted portion 105 is extremely narrow, the escape passages for the gas into the vent shaft 53 are also restricted to the same degree thereby subjecting the arc which may have moved to a point adjacent the barriers to a high velocity of flow or cross blast, which insures arc interruption at the time of current zero in the current wave of the arc.

The deionization of the arc while in the restricted portion 105 is especially rapid, due to the rapid rate at which dielectric strength is being built up along the arc stream. The oil pockets 65 along the walls of the passage provide an adequate supply of arc-extinguishing liquid, which when acted upon by the arc, produces sufficient quantities of un-ionized gas and liquid particles which are turbulently intermixed with the ionized particles of the arc stream, thereby causing a loss of ions so as to prevent the reignition of the arc after current zero. The particular arc interrupting device is efficient for the reason that the arc energy is maintained at a low value, particularly at the current peak of the arc. This is accomplished by maintaining the arc in a relatively unrestricted passage during the time of peak current or during that portion of the current wave when appreciable instantaneous current is flowing. The action of the piston which is moved simultaneously with the movable contact, causes the flow of arc-extinguishing liquid longitudinally in the arc stream, thereby sweeping the products of decomposition of the arc from the arc passage substantially at the rate in which these products are formed; thereby the internal pressure of the arc-extinguishing unit is maintained at a low value; and circuit interruption is effected at a time most favorable for arc extinction by subjecting the arc to strong cross blasts of un-ionized gas and liquid particles just prior to current zero. The particular venting arrangement for directing the gas and oil laterally through the arc are also of importance in effecting the improved interrupting qualities of the arc-extinguishing units.

The foregoing description of the operation of the interrupter has dealt primarily with the interrupting operation within each of the arc rupturing units 29. During the opening movement of the interrupter, operating rod 139, pistons 123, contacts 125 and the contact actuating member 153 move downwardly as a unit until the con-

tacts 125 engage the bottom of the slots 97 in the lower plate 95 of their respective units. The contact actuating member 153, however, is free to continue its downward movement until its lower end engages the base of the casing 1. This additional movement permits the contact actuating member 153 to separate from the contact fingers 151 to thereby place an additional gap in the electrical circuit as shown in Fig. 27. Inasmuch as 5 arc extinction within the arc rupturing units 29 takes place within a relatively short period of time, the circuit will have been interrupted prior to the separation of the contact actuating member 153 and the contact fingers 151. Thus the break 10 between the contact fingers 157 and the contact member 153 provides further insulation in the circuit and insures a higher factor of safety 15 against breakdown when the interrupter is in the open circuit position.

20 In closing the breaker, the contact actuating member 153 is operated upwardly by the mechanism 159 into engagement with the contact fingers 151 and the coupling member 129 of the lower arc extinguishing unit 29. Continued upward movement of the member 153 carries the movable contacts 125 with their pistons 123 to the closed circuit position against the bias of the accelerating spring 147. In the closed circuit position, contact pressure between the stationary contact 115 and the movable contacts 125 is maintained by the spring 113. These springs also assist the accelerating spring 147 in overcoming the inertia of the moving contact assemblage at the beginning of the circuit opening 30 operation.

35 A modified form of arc-extinguishing unit is shown in Figs. 24 to 27 inclusive. This unit is substantially like the units previously described, with the exception that the oil circulating piston 40 191 is adapted to operate within a cylindrical passage 193, which communicates with the arc passage 195 only at its upper and lower ends as shown at 197 and 199, respectively. The stationary contact 201 in this instance is provided 45 with an aperture 203 extending axially thereof to the exterior of the arc-extinguishing unit. The aperture 203 provides ready means for venting the products of decomposition of the arc during its maintenance between the contact 201 and the 50 movable contact 205.

55 As shown in Fig. 24, the movable contact 205 enters the lower plate 207 and is supported by a bracket 209 secured to the operating rod 211. Operating rod 211 extends axially through the passage 193 and also carries the piston 191. The upper plate 213 of the unit carries the upper arc horn 215 which has passages therethrough indicated at 217, which are adapted to communicate with a lateral passage 219 in the plate 213, 60 which in turn, communicates with the passage 197 leading to the cylindrical passage 193. It will thus be seen that as the arc is established in the passage 195, internal pressure within the passage will react through the passages 217, 219, 65 197 and in back of piston 191, thereby tending to equalize the reactive force on the forward side of the piston 191.

70 By utilizing the internal pressure of the interrupting unit to assist in actuating the piston 191 to the open circuit position, the external force required to actuate the interrupter to the open position is greatly reduced. Thus a large volume of oil may be circulated with relatively small 75 actuating force upon the operating rod 211. The arc-extinguishing operation in other respects for

the interrupter of the type shown in Figs. 24 to 26 is substantially the same as the operation of the arc-extinguishing unit previously described.

Although we have shown and described specific arrangements of arc-extinguishing units and their disposition within a circuit interrupter housing, it is to be understood that the same was for the purpose of illustration and that changes and modifications may be made in both structure and the arrangement thereof by those skilled in the art, without departing from the spirit and scope of the appended claims.

We claim as our invention:

1. The method of extinguishing an arc which has been established within an arc extinguishing liquid comprising, positively moving a quantity of liquid into engagement with the arc for displacing the products of decomposition of the arc from the region thereof without substantially disturbing the continuity of the arc stream, moving the arc laterally through the liquid upon the occurrence of predetermined conditions, and finally subjecting the arc to intense blasts of liquid and the products of decomposition of the arc to break up the continuity of the arc stream.

2. The method of extinguishing an arc which has been established within an arc extinguishing liquid comprising, positively circulating a quantity of liquid in close proximity to the arc to displace the products of decomposition of the arc from the region thereof without causing substantial penetration of the liquid into the arc core, moving the arc laterally through the liquid and constricting its cross section and finally forcing the products of decomposition of the arc and liquid into and through the arc core to break the continuity of the arc stream.

3. The method of interrupting an electrical circuit comprising establishing an arc within an arc-extinguishing liquid, subjecting the arc stream to a substantially longitudinal flow of insulating liquid until a predetermined time before current zero, moving said arc laterally and constricting its cross section and finally subjecting the arc to a cross blast of insulating liquid while in said constricted condition.

4. The method of interrupting an electrical circuit comprising establishing an arc within an arc-extinguishing liquid, displacing the products of decomposition of said arc longitudinally thereof at a rate substantially equal to the rate of formation of said products, moving said arc laterally when it has reached a predetermined cross-sectional area and subjecting the moving arc to a cross blast of the products of decomposition formed during such lateral movement.

5. The method of interrupting an electrical circuit comprising establishing an arc within an insulating liquid, maintaining the arc at least during the flow of maximum current in the current wave substantially free from cross blasts of gas by removing the gas longitudinally of the arc stream substantially as rapidly as it is formed, moving the arc laterally in the insulating liquid when it has reached a predetermined cross-sectional area and finally subjecting the arc to a cross blast of gas during such lateral movement.

6. The method of interrupting an electrical circuit comprising establishing an arc within an arc-extinguishing liquid, maintaining the arc in a predetermined position during at least the flow of peak current in the current wave, removing the gas generated by the arc from the arc stream longitudinally thereof at a rate substantially equal to the rate of formation of said gas, mov-

ing the arc laterally in the liquid from said predetermined position and finally subjecting the arc to a combined cross blast of gas and liquid during said lateral movement.

- 5 7. The method of interrupting an electrical circuit comprising establishing an arc within an insulating liquid, holding the arc in a predetermined position until the cross-sectional area thereof has been reduced to a predetermined 10 value, positively moving a stream of liquid longitudinally of the arc while the arc is in said predetermined position for removing the products of decomposition of the arc substantially as rapidly as said products are formed, moving the arc laterally through the liquid from said predetermined 15 position and finally subjecting the arc to a combined cross blast of liquid and the products of decomposition of the arc during said lateral movement.
- 20 8. In a circuit interrupter, means at least partially of insulating material defining a substantially completely enclosed arc passage, an insulating liquid within said passage, separable contacts for establishing an arc within said passage, means 25 maintaining said arc in a predetermined position during the initial stage of arc interruption, means for positively moving a quantity of insulating liquid into engagement with said arc without substantially breaking the continuity of the arc 30 stream while the arc is in said predetermined position, means for subsequently moving the arc laterally through said liquid and means for subjecting the arc to a turbulent flow of gas produced by the action of the arc on said liquid during 35 the lateral movement of the arc.

9. In a circuit interrupter, means at least partially of insulating material defining a substantially completely enclosed arc passage, an insulating liquid within said passage, separable contacts for establishing an arc within said passage, means maintaining said arc in a predetermined position during the initial stage of arc interruption, venting means for said passage causing the products of decomposition of the arc to flow longitudinally of the arc while it is in said predetermined position, means for subsequently moving the arc laterally through said liquid and means for further venting the passage to cause the products of decomposition of the arc to flow laterally through the arc during said lateral movement of the arc.

10. In a circuit interrupter, means at least partially of insulating material defining a substantially completely enclosed arc passage, an insulating liquid within said passage, separable contacts for establishing an arc within said passage, means maintaining said arc in a predetermined position during the initial stage of arc interruption, a piston associated with said passage and operative during the establishment of said arc to positively move a quantity of insulating liquid longitudinally of said arc while said arc is in said predetermined position, means for subsequently moving said arc laterally through said liquid and means for directing a combined blast of insulating liquid and gas resulting from the action of said arc upon the liquid laterally through the arc during lateral movement thereof.

11. In a circuit interrupter, a body of insulating liquid, means of insulating material immersed in said liquid for defining an arc passage, said passage having an enlarged portion and a restricted slot-like portion, separable contacts for establishing an arc in said enlarged portion, means biasing the arc laterally toward said restricted por-

tion, said restricted portion being sufficiently narrow to prevent arcs entering therein during the period of instantaneous currents above a predetermined value, said biasing means moving the arc laterally into said restricted portion following the reduction of instantaneous currents below said predetermined value, and vent means adjacent the rearward portion of said restricted portion of said passage for causing the products of decomposition of the arc to flow laterally through the arc stream in escaping from the passage.

12. In a circuit interrupter, a body of insulating liquid, means of insulating material immersed in said liquid for defining an arc passage, said passage having an enlarged portion and a restricted slot-like portion, separable contacts for establishing an arc in said enlarged portion, means biasing the arc laterally toward said restricted portion, said restricted portion being sufficiently narrow to prevent arcs entering therein during the period of instantaneous currents above a predetermined value, vent means for causing the products of decomposition produced by the arc while the latter is maintained within said enlarged portion of the arc passage to flow longitudinally of the arc stream in escaping from the passage, said biasing means moving the arc laterally into said restricted portion following the reduction of instantaneous current below said predetermined value and additional vent means adjacent the rearward portion of said restricted portion of the arc passage for causing the products of decomposition of the arc produced during lateral movement thereof to flow laterally through the arc stream in escaping from the arc passage.

13. In a circuit interrupter, a body of insulating liquid, means of insulating material immersed in said liquid for defining an arc passage, said passage having an enlarged portion and a restricted slot-like portion, separable contacts for establishing an arc in said enlarged portion, means biasing the arc laterally toward said restricted portion, said restricted portion being sufficiently narrow to prevent arcs entering therein during the period of instantaneous currents above a predetermined value, a vent opening adjacent one end of the enlarged portion of said arc passage, means for positively moving a quantity of liquid longitudinally of the arc while the arc is within said enlarged portion of the arc passage for expelling the products of decomposition of the arc from said enlarged portion of the arc passage through said vent opening, and additional vent openings adjacent the rearward portion of said restricted portion of the arc passage for causing the products of decomposition produced during lateral movement of the arc within said restricted portion of the arc passage to be blown laterally through the arc stream.

14. In a circuit interrupter, a body of arc-extinguishing liquid, an arc-extinguishing unit immersed in said liquid comprising means of insulating material defining an arc passage, said arc passage having an enlarged portion and a restricted slot-like portion, a pair of contacts within said enlarged portion, at least one of said contacts being movable to establish an arc within said enlarged portion, means biasing said arc laterally toward the restricted portion of said passage, said restricted portion being sufficiently narrow to prevent arcs of cross-sectional area greater than a predetermined cross-sectional area to be moved therein by said biasing means, means actuated simultaneously with said movable contact for

- positively moving a quantity of liquid longitudinally of the arc while the arc is retained within the enlarged portion of said arc passage, and means for causing liquid to flow laterally through 5 the arc stream following the entrance of the arc into the restricted portion of the arc passage.
15. In a circuit interrupter, a body of arc-extinguishing liquid, an arc-extinguishing unit immersed in said liquid comprising means of insulating material defining an arc passage, said arc passage having an enlarged portion and a restricted slot-like portion, a pair of contacts within said enlarged portion, at least one of said contacts being movable to establish an arc within said 10 15 enlarged portion, means biasing said arc laterally toward the restricted portion of said passage, said restricted portion being sufficiently narrow to prevent arcs of cross-sectional area greater than a predetermined cross-sectional area to be moved 20 therein by said biasing means, a vent opening adjacent one end of said enlarged portion of the arc passage, a piston operative in accordance with predetermined movement of said movable contact for driving arc-extinguishing liquid along the 25 longitudinal axis of the arc to expel the products of decomposition of the arc through said vent opening during the time said arc is retained in said enlarged portion, said biasing means assisted by the flow of arc-extinguishing liquid moving 30 said arc laterally into said restricted portion following a reduction of the cross-sectional area of said arc below said predetermined cross-sectional area, and additional vent openings disposed rearwardly of said restricted portion of the arc passage 35 sage for causing the products of decomposition of the arc during its lateral movement within said restricted portion to flow laterally through the arc stream.
16. In a circuit interrupter, a body of arc-extinguishing liquid, means of insulating material immersed in said liquid defining a narrow arc chamber and a cylindrical passage communicating with said chamber, a piston movable in said cylindrical passage, a stationary contact extending 40 45 into said chamber, a cooperating contact movable for establishing an arc within said chamber, means for moving said arc laterally within said chamber upon the occurrence of predetermined conditions, actuating means for operating said cooperating movable contact to establish the arc and for operating said piston to move a quantity of arc-extinguishing liquid longitudinally of the arc prior to movement of the arc laterally in said chamber, and means for venting said chamber to cause the products of decomposition of the 50 55 arc to flow laterally through the moving arc in escaping from the chamber.
17. In a circuit interrupter, a body of arc-extinguishing liquid, means of insulating material immersed in said liquid defining a narrow arc chamber and a cylindrical passage having continuous communication with said chamber adjacent one side thereof, a stationary contact within said chamber adjacent said cylindrical passage, a piston movable in said cylindrical passage, an operating rod for said piston, a cooperating contact carried by said operating rod disposed adjacent one end of said piston and adapted to be moved by said rod into and out of engagement with said 60 65 stationary contact, means for actuating said rod to simultaneously establish an arc within said chamber and to cause said piston to move a quantity of arc-extinguishing liquid longitudinally of the arc and means for moving the arc laterally 70 75 within said arc chamber.
18. In a circuit interrupter, a body of arc-extinguishing liquid, means of insulating material immersed in said liquid defining a narrow arc chamber and a cylindrical passage having continuous communication with said chamber adjacent one side thereof, a stationary contact within said chamber adjacent said cylindrical passage, a piston movable in said cylindrical passage, an operating rod for said piston, a cooperating contact carried by said operating rod disposed adjacent one end of said piston and adapted to be moved by said rod into and out of engagement with said stationary contact, means for actuating said rod to simultaneously establish an arc within said chamber and to cause said piston to move a 15 20 25 30 35 40 45 50 55 60 65 70 75 quantity of arc-extinguishing liquid longitudinally of the arc, means for moving the arc laterally within said arc chamber in response to predetermined conditions, and means for venting one side of said arc chamber to cause a lateral flow of gas through the arc stream as the arc is moved within said arc chamber.
19. In a circuit interrupter, a body of arc-extinguishing liquid, means of insulating material immersed in said liquid defining a narrow arc chamber and a cylindrical passage having continuous communication with said chamber adjacent one side thereof, said arc chamber having a restricted slot-like portion and an enlarged portion of greater width, said enlarged portion being adjacent said cylindrical passage, a stationary contact within the enlarged portion adjacent said cylindrical passage, an operating rod movable through said cylindrical passage, a cooperating contact carried by said operating rod and adapted to be actuated thereby into and out of engagement with said stationary contact, a piston carried by said operating rod and movable in said cylindrical passage, venting means adjacent one end of the enlarged portion of said arc chamber, actuating means for said operating rod for causing a predetermined separation of said contacts to establish an arc within the enlarged portion of said arc chamber and to cause said piston to move a quantity of arc-extinguishing liquid longitudinally of the arc, said moving arc-extinguishing liquid expelling the products of decomposition of the arc through said venting means, means for moving said arc laterally into the restricted portion of the arc chamber in response to predetermined conditions and means for venting one side of said restricted portion of the arc chamber to cause the products of decomposition of the arc resulting from movement of the arc laterally within said restricted portion to flow laterally through the arc stream.
20. In a circuit interrupter, a body of arc-extinguishing liquid, means of insulating material immersed in said liquid defining a narrow arc chamber and a cylindrical passage, each end of said cylindrical passage having a fluid connection with said arc chamber, a piston in said cylindrical passage movable between said fluid connections, a stationary contact extending into said chamber, a cooperating contact movable for establishing an arc within said chamber, means for moving said arc laterally within said chamber upon the occurrence of predetermined conditions, actuating means for operating said cooperating movable contact to establish the arc and for operating said piston to move a quantity of arc-extinguishing liquid from said cylindrical passage through one of said connections longitudinally of the arc prior to movement of the arc laterally in said chamber, and means for vent-

ing said chamber to cause the products of decomposition of the arc to flow laterally through the moving arc in escaping from said chamber, said fluid connections from said arc chamber to said 5 cylindrical passage causing the pressure within said arc chamber to react substantially equally upon both sides of said piston.

21. The method of interrupting an electrical circuit comprising, establishing an arc within an 10 arc extinguishing liquid, maintaining the arc in a predetermined position until a predetermined time before current zero, subjecting the arc stream to a mild blast of arc extinguishing liquid when in said predetermined position, moving the 15 arc in one section from said predetermined position and constricting its cross section and finally subjecting the arc to an intense blast of arc extinguishing liquid while in said constricted condition.

22. In a circuit interrupter, a body of arc extinguishing liquid, means of insulating material immersed in said liquid defining an arc chamber, a pair of separable contacts within said arc chamber for establishing an arc therein, a piston chamber having a fluid connection with each end of 25 said arc chamber, a piston movable within said piston chamber, and actuating means for operating said contacts for establishing the arc and for operating said piston to move a quantity of arc

extinguishing liquid from said piston chamber through one of said connections into engagement with the arc stream, said fluid connections from 5 said arc chamber to said piston chamber causing the pressure within said arc chamber to react substantially equally upon both sides of said piston.

23. In a circuit interrupter, a body of arc extinguishing liquid, means of insulating material immersed in said liquid defining a narrow arc chamber, a pair of separable contacts within said arc chamber for establishing an arc therein, means for moving the arc laterally within said arc chamber upon the occurrence of predetermined conditions, a piston chamber having a fluid connection with each end of said arc chamber, a piston movable within said piston chamber, and actuating means for operating said contacts to establish the arc and for operating said piston to move a quantity of arc extinguishing liquid from said piston chamber through one of said connections into engagement with the arc stream prior to movement of the arc laterally in said arc chamber, said fluid connections from said arc chamber to said piston chamber causing the pressure within 20 25 said arc chamber to react substantially equally upon both sides of said piston.
